UNITED STATES PATENT OFFICE.

MICHAEL ASCHERL, OF CLEVELAND, OHIO.

DESIGN FOR A BOOK END.

Application filed February 10, 1923. Serial No. 5,149. Term of patent 7 years.

To all whom it may concern:

Be it known that I, MICHAEL ASCHERL, a citizen of the German Republic, residing at 2098 W. 38 St., Cleveland, in the county of Cuyahoga and State of Ohio, have invented a new, original, and ornamental Design for a Book End, of which the following is a specification, reference being had to the accompanying drawing, forming part thereof.

The figure is a perspective view of a book end embodying my new and ornamental design.

I claim:

The ornamental design for a book end as shown.

MICHAEL ASCHERL.

Witnesses:

LORETTA SCHUERGER,
ANNA A. LUTTON.
